CHIMNEY CONNECTOR

Arthur H. Klein, Milwaukee, Wis.

Application May 21, 1937, Serial No. 143,917

5 Claims. (Cl. 126—314)

This invention relates to furnaces and boilers and more particularly to a connector between a furnace or boiler smoke pipe and a chimney.

The usually accepted method of making the connection between a smoke pipe and a chimney is to make a circular hole in the side of the chimney and cement the smoke pipe directly in the hole.

Some attempts have been made to improve on this obviously crude method by cementing a permanent thimble in the chimney hole, and providing some sort of a collar for the smoke pipe which is fastened onto the thimble by bolts. These devices have been unsuccessful for various reasons, but primarily because of the difficulty of removing the smoke pipe for cleaning. The bolts rust and freeze the collar in place, and necessitate cutting off the bolts with a cold chisel in order to clean or repair the flue.

One object of the present invention is to provide a smoke pipe connector which will hold the smoke pipe firmly in place in the chimney without the use of bolts.

Another object of the invention is to provide a smoke pipe connector which will simplify the process of taking apart and assembling the smoke pipe with the chimney.

A further object is to provide a connector between a smoke pipe and a chimney which will positively grip and hold the smoke pipe.

Another object is to provide a connector between a smoke pipe and a chimney which can be readily disassembled.

Another object is to provide a connector between a smoke pipe and a chimney, including a thimble fixed in the chimney and a collar surrounding the smoke pipe, in which insertion of the collar in the thimble fixes the collar in the thimble and clamps the smoke pipe in the collar simultaneously.

These and other objects, the nature of which will become apparent as the description of the invention progresses, are accomplished by means of the preferred form of the invention shown on the accompanying drawing and described in the following specification, and such modifications thereof as may fall within the scope of the appended claims.

In the drawing:

Fig. 1 is a cross-section through the center of a smoke pipe and thimble, and is a cross-section on the line 1—1 of Fig. 2, one half of the chimney collar being shown in side elevation; and

Fig. 2 is a rear plan view of the connector, as seen from within the chimney.

In the drawing, in which like numerals indicate like parts in both views, a thimble 5 is shown grouted into the base of a chimney 6. The thimble is preferably made square because of the ease of forming a square hole in the brickwork of the chimney, but may be other shapes if desired.

The thimble 5 has one or more wedge surfaces 7 on the interior of each side of the thimble. The wedge surfaces or wedges 7 engage cooperating wedge surfaces or wedges 8 on a collar 9 to force the collar 9 into engagement with a smoke pipe 10 and simultaneously wedge the collar 9 in the thimble 5.

The collar 9 is made in two identical halves and comprises a cover plate 11 with a central 15 hole 12 therein to receive the smoke pipe 10, and a skirt 13 which surrounds the exterior of the hole 12 and supports the wedges 8. One half the hole 12 is formed in each half of the collar 9 so that the collar can be put in place around 20 the smoke pipe 10 after the smoke pipe has been inserted in the thimble 5.

The cover plate 11 is of sufficient size to form a complete cover for the thimble 5 and prevent the escape of smoke from the chimney or any 25 excess air filtering in between the cover 11 and the thimble 5.

By making the collar 9 in two halves, the wedges 7 and 8 force the halves into engagement with the pipe 10 and form a tight joint between 30 the pipe and the collar and simultaneously fix the collar in the thimble 5. A further advantage accruing from the use of the split collar is the ease with which the smoke pipe can be adjusted and assembled in the connector.

In use, the smoke pipe 10 is adjusted on the furnace (not shown) with the free outer end inserted through the thimble 5. One half of the collar 9 is then placed about the pipe 10 and forced into place in the thimble. The other half of the collar 9 is then placed on the pipe 10 and the collar inserted into the thimble 5. As the second half of the collar is put in place in the thimble, the wedges on both sides of the thimble cooperate with corresponding wedges on the collar to clamp the pipe in the collar. At the same time the wedges grip the collar and hold it securely in the thimble without the use of bolts and nuts or other fastening means.

Having thus described the invention, it is apparent that it is susceptible to various changes and modifications. It is not, therefore, desired to limit the invention to the precise form herein shown and described but only by the scope of the appended claims.

What is claimed as new and desired to secure by Letters Patent is:

1. A smoke pipe connector adapted to secure a smoke pipe in a chimney, comprising, a thimble fixed in the chimney, a collar formed of two pieces having an opening therein adapted to receive the smoke pipe, and means on said thimble cooperating with means on the collar to urge said pieces of the collar into gripping engagement with the smoke pipe.
2. A smoke pipe connector adapted to connect a smoke pipe to a chimney, comprising, a thimble secured in the chimney, a wedge surface formed within said thimble, a collar adapted to surround the smoke pipe and to fit within the thimble, and a wedge member formed on said collar and adapted to engage with said first named wedge member to secure the thimble and collar in assembled relationship.
3. A smoke pipe connector adapted to connect a smoke pipe to a chimney, comprising, a thimble secured in the chimney, a wedge surface formed on the interior of said thimble, a collar formed of two parts having an opening to receive the smoke pipe a portion of said collar adapted to fit within the thimble, and a wedge surface

formed on one part of said collar adapted to cooperate with the first named wedge surface to simultaneously secure the collar in the thimble and clamp the smoke pipe in the collar.

4. A smoke pipe connector of the character described comprising, a thimble adapted to be secured in an opening in a chimney, a plurality of wedges formed on the interior of said thimble, a collar having an opening therein adapted to receive a smoke pipe, and a plurality of wedges carried by said collar surrounding said opening and adapted to cooperate with the wedges on the thimble to hold the thimble and collar in assembled relationship.

5. A smoke pipe connector of the character described comprising, a thimble adapted to be secured in an opening in a chimney, a plurality of wedges formed on the interior of said thimble, a collar having a hole therein adapted to receive a smoke pipe, a skirt surrounding said hole, and a plurality of wedges carried by said skirt adapted to engage the wedges on the thimble to simultaneously secure the smoke pipe in the collar and the collar in the thimble.

ARTHUR H. KLEIN.
